UNITED STATES PATENT OFFICE.

JAMES A. MALONEY, OF WASHINGTON, DISTRICT OF COLUMBIA.

ELECTRIC TELEPHONE-TRANSMITTER.

SPECIFICATION forming part of Letters Patent No. 296,593, dated April 8, 1884.

Application filed July 11, 1883. (No model.)

To all whom it may concern:

Be it known that I, JAMES A. MALONEY, of Washington city, in the District of Columbia, have invented certain new and useful Improvements in Electric Telephone-Transmitters, of which the following is a specification.

My improvements have particular reference to a telephone-transmitter of the type illustrated in Letters Patent No. 274,353, dated 10 March 20, 1883, although they are in some respects susceptible of application to transmitters of other types.

The invention is directed, mainly, to an improved construction and arrangement of the contact-points through which the impulses, due to the vibrations of the diaphragm are transmitted to line, and it is characterized, principally, by the combination, with the diaphragm, of a contact-point, a spring-acting carrier therefor attached to and moving with the diaphragm, and a controlling device—termed by me a “stirrup”—which bears upon the spring-carrier, and during the vibrations of the latter operates to direct its movements to 25 and from the stationary contact-point in connection with which the carrier contact-point works. The organization just outlined is very efficient and sensitive in practical operation, and responds to the slightest movements of the 30 diaphragm.

The nature of my invention and the manner in which the same is or may be carried into effect can best be explained and understood by reference to the accompanying drawings, 35 in which—

Figure 1 is a side elevation of the transmitter with the side of the box or case removed. Fig. 2 is a rear elevation of the working parts with the back of the case cut away or removed. 40 Fig. 3 represents on enlarged scale a cross-section of the removable rear contact-point and the lower part of the stem of its carrier, together with an elevation of part of the stationary contact-point in connection with which it works. Fig. 4 is a plan of the movable contact-point. Fig. 5 is a front sectional elevation on enlarged scale of the transmitter, representing diagrammatically the circuit-connections. Fig. 6 is an enlarged sectional eleva-

tion of the lower part of the carrier-stem, to be 50 hereinafter referred to.

A is the case of the instrument, the front wall, A', of which is covered by the hinged door A², the voice-opening being formed through both A' and A², as indicated by dotted lines in Fig. 1. 55 The door A is provided to allow access to be had to the front contact-point for the purpose of adjusting it, &c. B is the diaphragm, made of a thin sheet of any proper material—in this instance wood. It is attached at its top and 60 bottom to suitable cleats or supports, a, between which and the diaphragm are interposed buffers or cushions a' of vulcanized rubber or other suitable elastic material, for the purpose of preventing the diaphragm from 65 being influenced by extraneous vibrations transmitted through the case A from the wall or other part to which the case is attached. On the front of the diaphragm is fixed a point or plate, c', of conducting material—platinum 70 in this instance—and opposite c' is the carbon point c, carried by an arm, c², of spring metal, which is pressed toward the diaphragm by an adjusting-screw, c³. Upon the rear face of the diaphragm is another contact-point, designed 75 to operate in connection with a stationary contact-point, d, consisting in this instance of a cylinder, d', of brass or other metal, into the top of which is screwed or inserted a disk, d², of platinum, which latter is the contact-point 80 proper. The cylinder is carried by an adjusting screw-stem, d³, which screws through a metal bracket, d⁴, and is provided with a lock-nut, d⁵. By this means the contact d can be 85 adjusted up and down with great nicety.

I now proceed to describe the contact which operates in connection with d. It may be described in a general way as consisting of a carbon button or disk, e, (the contact-point proper,) which is supported by a bent spring-acting carrier-stem, f, of metal or other good conducting material, attached to diaphragm B. The stem, at its upper end, where it is attached to the diaphragm, is for a portion of its length 90 horizontal. At its lower end, where the button e is, it is for a portion of its length vertical, so as to directly overhang the part d, thus allowing the button or disk e to make at the nec-

essary times square contact with the platinum disk d^2 , and its intermediate portion, f' , extends diagonally between the two end portions, and is flattened, so as to in effect be a spring-strip, 5 for the purpose about to be explained.

Under the arrangement thus far described it will be seen that when the diaphragm is in vibration the effect will be to move the contact e to and fro across or above the face of 10 stationary contact d . In order to translate this motion of contact e into an up-and-down movement, or a movement to and from stationary contact d , I make use of a controlling device, or, as I have hereinbefore termed it, 15 a "stirrup," which is shown at g . This stirrup consists of a stiff strip of metal or other suitable material, which, at its upper end, is attached to the upper wooden cross-cleat or support, a , and thence extends down so that 20 its lower end shall bear down upon the slanting springy portion f' of carrier f . The lower end of the stirrup is forked, so as to straddle the part f' , and thus to guide and prevent lateral movement of the carrier; and its upper 25 end is held to the part a by a slot and set-screw connection, f^2 , whereby the stirrup can be vertically adjusted with a view to assuring it in proper position with respect to the carrier. Under this arrangement it will be seen that 30 the stirrup, when the carrier moves with the diaphragm, will act to depress it and permit it to rise according to the direction of its movement, thus causing contact e to have motion to and from the other contact, d . I here remark that this arrangement manifestly is applicable not only to the transmitter herein shown, but also to any other instruments in which microphonic contact is required. The 35 contact e may be in one piece with or solidly attached to its carrier, if desired; but I very much prefer to have it loosely connected therewith, the connection being such that it is virtually suspended from the carrier with capacity for up-and-down movement with relation 40 thereto. The preferred arrangement for this purpose is illustrated in the drawings. Into the lower end of the carrier arm or stem is screwed a short shank, h , of carbon, having a head, h' , on its lower end. Upon this shank, 45 is loosely mounted the carbon disk or button e , which is formed with a hole, e' , for the passage of shank h , and with a recess, e^2 , on its under side to receive the head h' . In order to 50 prevent the disk from rotating on the shank 5. the latter has a square or other equivalent form in cross-section, and the hole e' is of corresponding shape, as indicated in Fig. 4. In this way the disk e is loosely suspended from the carrier. The latter acts only to lift it, 55 while its descent is due to gravity. I find that this arrangement is productive of most excellent results, and in practice is much to be preferred over a rigidly-connected contact-point.

I have indicated what I deem to be a good form of stationary contact, d , to operate in connection with the movable contact just de-

scribed; but I do not desire to be understood as restricting myself to that special form.

The circuit-connections and the adjustments are in the transmitter shown in the drawings 70 to the same as those illustrated in the Letters Patent hereinbefore referred to.

Battery E, Fig. 5, having one pole grounded, is in circuit with the condenser F through wire 1, binding-post C, wire 3, (leading from C 75 to arm c^2), front contact-points, $c c'$, wires 8-4, (the former extending between c' and the upper end of carrier f , and the latter from f to center binding-post, B'), post B', and wire 2; and the condenser discharges to line through 80 wire 2, post B', wire 4, rear contact-points, $e d$, wire 5, binding-post D, and line-wire 6. The normal adjustment of parts is such that the points $c c'$ have full contact, while the points $d e$ have only partial or incomplete contact. 85

The principle of operation of the transmitter is fully set forth in the Letters Patent hereinbefore referred to, and requires no further explanation here. It is sufficient to say that when the instrument is used both the circuit 90 through which the battery charges the condenser and the circuit through which the condenser discharges to line are completed through the transmitter. The vibrations of the diaphragm result in alternately charging the condenser from the battery and discharging the condenser to line, thus transmitting over the line-wire a series of electrical impulses with the effect of reproducing the voice at the receiving-station. 95

100

Having described my improvements and the best way now known to me of carrying the same into practical effect, I state in conclusion that I do not restrict myself to the mechanical details hereinbefore described, and shown in 105 illustration of my invention; but

What I claim, and desire to secure by Letters Patent, is—

1. The combination, with the diaphragm, of a spring-acting carrier mounted on the diaphragm, a contact-point connected or attached to said carrier, and a stirrup for controlling the movements of the carrier, substantially as and for the purpose hereinbefore set forth. 110

2. The combination, with the diaphragm, 115 the spring-acting carrier, and its contact-point, of a stirrup adjustable with relation to said carrier, substantially as and for the purposes hereinbefore set forth.

3. The diaphragm, the bent spring-acting carrier, and its contact-point, in combination with a stationary contact-point to operate in connection with the carrier contact-point, and a stirrup which controls and directs the movement of the carrier to and from the stationary 120 contact-point, substantially as hereinbefore set forth.

4. The combination, with the diaphragm and the spring-acting carrier, of a contact disk or button loosely mounted on or suspended 125 from said carrier, substantially as and for the purposes hereinbefore set forth.

5. The combination of the diaphragm, the spring-acting carrier, the contact disk or button suspended from or loosely mounted on said carrier, the stirrup for controlling the movements of the carrier, and the stationary contact-point, substantially as and for the purposes hereinbefore set forth.

6. The combination of the diaphragm, the bent spring-acting carrier, the contact disk or button suspended from or loosely mounted on the lower end of the same, so as to be capable of independent vertical movement without rotation, the carrier-controlling stirrup, and the stationary contact-point, substantially as and for the purposes hereinbefore set forth.

15 7. The combination of the diaphragm, the

carrier-stem *f*, secured thereto, and provided with a slanting spring portion, *f'*, intermediate between its upper horizontal and lower vertical ends, the contact button or disk loosely mounted on the lower end of said carrier-stem, the controlling-stirrup *g*, adapted to operate against or in connection with the spring portion *f'*, and the stationary contact-point, for joint operation substantially as hereinbefore set forth.

In testimony whereof I have hereunto set my hand this 5th day of July, 1883.

JAMES A. MALONEY.
